CLAIM

The ornamental design for a pet climbing ladder, as shown and described.

DESCRIPTION

FIG. 1 is a front elevation view of a pet climbing ladder, showing my new design;
FIG. 2 is a rear elevation view thereof;
FIG. 3 is a top plan view thereof;
FIG. 4 is a bottom plan view thereof;
FIG. 5 is a left side elevation view thereof;
FIG. 6 is a right side elevation view thereof;
FIG. 7 is a rear, bottom, and right side perspective view thereof;
FIG. 8 is a front, top, and left side perspective view thereof;
FIG. 9 is a front, top, and left side perspective view thereof, shown in an alternative configuration;
FIG. 10 is a rear, top, and left side perspective view thereof, shown in the alternative configuration; and,
FIG. 11 is a rear, bottom, and left side perspective view thereof, shown in the alternative configuration.
